UNITED STATES PATENT OFFICE.

THOMAS E. RODMAN, OF GLENCOE, ILLINOIS, ASSIGNOR TO THE BRADFORD CORPORATION, OF CHICAGO, ILLINOIS, A CORPORATION OF DELAWARE.

REVERSIBLE STRUT FOR BRAKE BEAMS.

Application filed September 13, 1926. Serial No. 135,175.

This invention relates to reversible struts for trussed brake beams for railway cars.

The main objects of this invention are to provide an improved form of strut capable of a limited rotation on its longitudinal axis, whereby the brake lever may be tilted to one side or the other as the particular location of the beam may require; and to provide improved means for locking the strut in either 10 position.

An illustrative embodiment of the invention is shown in the accompanying drawings, in which:

Fig. 1 is a plan view of a brake beam 15 having the improved reversible strut.

Fig. 2 is an end view of the head end of the strut.

Fig. 3 is an end view of the foot end of the strut seating the tension member.

20 Fig. 4 is a side elevation of a portion of the strut showing the foot end thereof.

Fig. 5 is a side elevation of the strut.

Fig. 6 is a similar elevation rotated on its axis and partly in section.

25 In the form shown, the brake beam comprises a compression member 1 and a tension member 2 secured together adjacent their outer ends in any suitable manner, as by the nuts 3 screwed on the ends of the tension member and bearing against the brake heads 4. A hollow tubular strut 5 separates the compression member and the tension member at points substantially equidistant from their respective ends. The head end 6 of the strut 30 is an elliptic cylinder fitting within the bosom of the channel bar compression member and shaped to guide and limit rotative movement of the strut with respect to the compression member. The strut has an annular shoulder 7 near the compression member. A lug 8 fits in the aperture or recess 9 in the compression member, which may be of channel bar or any other suitable rolled or pressed structural steel shape.

40 A sleeve 10 secures the strut to the compression member and is shaped to embrace the adjacent parts of both. The aperture 11 is of sufficient diameter to permit passing the strut therethrough, but the aperture 12

is smaller so that its edges overlap and engage the shoulder 7. The longitudinal bore for the compression member is of such depth that, with the strut in place, the sleeve may be slipped over the end of the compression member and slid into place. A wedge 13, 50 driven between the compression member and the sleeve serves to draw the lug 8 into the recess 9 and detachably secure the parts together. The wedge has at its thin end a lip 14, which may be bent upwardly after 55 it has been driven home, thereby serving to secure the several parts together.

The foot end of the strut has a seat 15 adapted to receive the tension member 2. The seat is formed to permit the desired degree of rotation for the strut, which rotation is also limited by longitudinally projecting feet 15.1 which straddle the tension member and engage opposite sides thereof.

Although but one specific embodiment of 70 this invention has been herein shown and described, it will be understood that numerous details of the construction shown may be altered or omitted without departing from the spirit of this invention as defined by the 75 following claims.

I claim:

1. A brake beam comprising a channelled compression member, a tension member, a reversible strut extending between said members, and having a head fitting into the channel of the compression member and of non-circular section to provide for and limit the axial rotation of the strut, a shoulder on the strut adjacent said head, and means embracing said shoulder and said compression member for securing said strut. 80

2. A brake beam comprising a channelled compression member, a tension member, a reversible strut extending between said members, and having a head fitting into the channel of the compression member and of non-circular section to provide for and limit the axial rotation of the strut, a shoulder on the strut adjacent said head, and a sleeve embracing said shoulder and said compression member for securing said strut. 90

3. A brake beam comprising a channelled

compression member, a tension member, a reversible strut extending between said members, and having a head fitting into the channel of the compression member and of non-circular section to provide for and limit the axial rotation of the strut, a shoulder on the strut adjacent said head, a sleeve embracing

said shoulder and said compression member for securing said strut, and a wedge between said sleeve and said compression member for detachably securing said strut. ¹⁰

Signed at Chicago this 9th day of September, 1926.

THOMAS E. RODMAN.
